LEWIS HAZLETT AND SAMUEL D. HAZLETT, OF WINFIELD TOWNSHIP, PENNSYLVANIA.

Letters Patent No. 96,805, dated November 16, 1869.

IMPROVEMENT IN PORTABLE FENCE.

The Schedule referred to in these Letters Patent and making part of the same.

To all whom it may concern:

Be it known that we, LEWIS HAZLETT and SAMUEL D. HAZLETT, of Winfield township, in the county of Butler, and State of Pennsylvania, have invented a new and useful "Improvement in Portable Fence and Gateway;" and we do hereby declare the following to be a full, clear, and exact description thereof, reference being had to the accompanying drawing, making a part of this specification, in which—

Figure 1 is a side view of contiguous sections, showing the common panel-joint;

Figure 2 is a side view of contiguous sections, showing the key or gateway-joint;

Figures 3 and 4 show, in section, the positions of the same interlocked and fastened; and

Figure 5 shows a bevelled cleat attached to a fence-rail.

The nature of our invention consists in an improved construction of a portable board fence, made as hereinafter described, in separate sections, and so that the adjacent ends of contiguous sections may be readily interlocked and fastened, and as readily unfastened and taken apart, for convenience in opening, moving, and shifting.

To enable others skilled in the art to make and use our invention, we will proceed to explain its construction and manner of use.

a represent the bars of a section of board fence, each section being made of any suitable length.

These are fastened together by cross-strips *b b'*.

The ends of the bars are halved or notched as at *a'*, and the cross-strips *b* are nailed on just at or back of the shoulder of the halving.

For merely fence-purposes we then attach bevel-faced cleats *c*, of the form shown in fig. 5, on the outer face of two or more of the ends *a'* of one section, so that the base or heel of each such cleat shall come at or a little forward of the shoulder of the halving.

Across the ends of the parts *a* of the next adjacent section, we attach a cross-strip, *d*, the inner face of this strip *d* and the outer face of the cross-strip *b* of the same section, being bevelled to any desired angle.

To enable us to insert the halved ends *a'*, to which the bevelled cleats *c* are attached, between the cross-strips *b* and *d*, we make notches *o* in the cross-strip *d*, fig. 2.

The ends of the former section, on which are fastened the cleats *c*, are then passed through the notches *o* between the ends *a'* of the latter section, and between the cross-pieces *b d*, as shown in fig. 1, the heels of the cleats *c* allowed to engage the cross-strip *d*, and the sections are straightened until the ends *a'* of the former section bear against the bevel faces of the cross-strips *b d*. The ends *a'* are, however, first slipped or dropped down below the notches *o*, till they occupy the position shown.

On the inside of one end of each section is fastened

a bevelled cross-strip, *e*, in such position as to press the ends of the boards back of the bevelled cleats, against the shoulders of the strip *b*. Then, to secure the sections tightly into position, we push forward and fasten the slide or pin *g*, as in fig. 2, which holds the bevel-faced cleats *c* down against the shoulders of the cross-piece *b* and the halved ends of the other section.

This description, it will be observed, is particularly applicable to the form of fence shown in fig. 2.

The construction of the joint shown in fig. 1, however, is exactly the same, as to the parts marked *a*, *b*, *c*, and *d*.

To interlock the sections of fig. 1, the further ends are brought nearer together, so that the cleated half bars *a'* may pass between the cross-strips *b d*, which latter being done, the further ends are separated until the ends *a'* bear, on the one side, against the strip *b*, and on the other, against the strip *d*, the heels of the cleats *c* resting also against the strip *d*.

The advantages of our invention are, its simplicity and cheapness of construction, and its convenience and adaptability to any surface.

In building our fence on uneven or sloping ground, the cross-pieces *b* being fastened to the rails *a* by a single nail, we rack or push over so as to make the cross-strips *b* stand plumb, and then secure them in that position by putting in another nail, or other convenient way.

If it is desired to take down, move, or shift it, all that is necessary is to draw out the sliding latch *g*, in fig. 2, and unhook and draw out the bevelled ends *a'* from each other. By thus taking out a single, panel or section, a gateway can be formed at any desired place.

It will be observed that for the purpose of making a gateway, by using the additional devices shown in fig. 2, such devices or additions are required on only one end of the gateway, panel, or section, its opposite end remaining the same as in fig. 1, as also the end of the panel with which it is interlocked.

What we claim as our invention, and desire to secure by Letters Patent, is—

1. In a portable fence, an interlocking joint, consisting of the ends *a'*, cleats *c*, and cross-strips *b d*, all arranged and used substantially in the manner set forth.

2. The subject-matter of the foregoing claim, in combination with the cross-strip *e*, notches *o*, and sliding catch *g*, all arranged and operated substantially as set forth.

In testimony whereof, we, the said LEWIS HAZLETT and SAMUEL D. HAZLETT, have hereunto set our hands.

LEWIS HAZLETT.
S. D. HAZLETT.
